[54] COMPOSITE PIPE FITTINGS AND THE PRODUCTION THEREOF

[76] Inventor: Richard L. Vockel, Jr., 151 Highgate St., Granville, Ohio 43023

[21] Appl. No.: 152,278

[22] Filed: May 22, 1980

[52] U.S. Cl. 285/156; 285/423; 285/DIG. 16; 285/55

[57] ABSTRACT

A composite pipe fitting and a method for producing it are provided by encasing a thermoplastic pipe fitting in a thermosetting material reinforced with discrete fibers with an adhesive material intermediate the thermoplastic pipe fitting and thermosetting material bonding the thermoplastic pipe fitting to the thermosetting material.
